MOP WRINGER

Charles Wegelin, Birmingham, Ala.

Application January 29, 1951, Serial No. 14,017

Term of patent 7 years

(Cl. D9—2)

To all whom it may concern:

Be it known that I, Charles Wegelin, a citizen of the United States, residing at Birmingham, State of Alabama, have invented a new, original, and ornamental Design for a Mop Wringer, of which the following is a specification, reference being had to the accompanying drawing, forming a part thereof.

Fig. 1 is a plan view of mop wringer showing my new design;

Fig. 2 is a side elevational view thereof;

Fig. 3 is an end elevational view thereof;

Fig. 4 is a sectional view taken along the line IV—IV of Fig 2; and

Fig. 5 is a sectional view taken along the line V—V of Fig. 2.

A pail supporting the mop wringer has been fragmentarily depicted in broken lines for convenience of illustration.

The dominant features of my new design reside in those portions shown in full lines.

I claim:

The ornamental design for a mop wringer, as shown and described.

CHARLES WEGELIN.
